UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

SUPERVISORY SYSTEM.

1,337,753.

Specification of Letters Patent. Patented Apr. 20, 1920.

Application filed November 27, 1916. Serial No. 133,627.

To all whom it may concern:

Be it known that I, HENRY P. CLAUSEN, a citizen of the United States, residing at Mount Vernon, in the county of Westchester and State of New York, have invented certain new and useful Improvements in Supervisory Systems, of which the following is a full, clear, concise, and exact description.

This invention relates to a supervisory system to be used in connection with telephone systems of the automatic type.

It is the object of this invention to provide means to convey information to a special operator if a switch fails to function properly at any stage of its operation.

A feature of the invention resides in the provision of means for preventing the release of a defective switch so that an attendant may observe at which point of its operation it failed, a signal at the same time being given to an operator, informing her of such failure. Added features will be found, due to the fact that an operator will be signaled under the following conditions:

25 First, if the called party does not answer within a reasonable period of time;

Second, if the called party is busy and the calling subscriber fails to release the connection, with the result that the busy-tone is allowed to operate for more than a predetermined length of time;

Third, if a switch fails to move in response to the primary set of impulses;

Fourth, if the switch responds to the primary set of impulses but fails to respond to the secondary set of impulses; and

Fifth, if the subscriber's call correctly operates the brush-carrying mechanism, but the ringing current fails to start.

40 It is thought that the invention will be best understood from the following detailed description, reference being had to the accompanying drawing.

In the drawing the invention is shown applied to a connector circuit.

The operation of the circuit disclosed in case of a successful call will first be described.

It has been assumed that the calling subscribers' lines are arranged to be extended directly to the connectors by means of line finders, the brushes of such a finder being indicated at 4, 5 and 6. In practice the calling line would be extended to the connector

by means of a selector or selectors. These 55 have been omitted for the sake of simplicity.

The subscriber at substation 1, desiring a connection with the subscriber at substation 2, removes his receiver from the hook, whereupon his line will be extended to the 60 connector by means of the line finder whose brushes are shown at 4, 5 and 6, and which operates in the well-known manner. As soon as the calling line has been extended to the connector, relay 7 is energized over a 65 circuit extending from grounded battery, upper winding of relay 7, lower armature and back contact of relay 8, finder brush 6 and its associated contact, over the loop of the calling subscriber's line, finder brush 5 70 and its associated contact, upper armature and back contact of relay 8, lower winding of relay 7, to ground. Relay 7 is energized and completes an energizing circuit at its armature and front contact for slow release 75 relay 9.

The subscriber now operates his impulse transmitter, indicated at 3, to send the first series of impulses. This first interruption of the line circuit causes the deenergization 80 of relay 7 and completes a circuit from ground, armature and back contact of relay 7, lower armature and front contact of relay 9, which, being slow to release, retains its armature during the short interruptions in 85 the line circuit, winding of relay 10, winding of primary stepping magnet 11, side-switch wiper 12 in its first position, to grounded battery. Slow release relay 10 is energized in this circuit and completes an 90 energizing circuit for escape magnet 13 from grounded battery, upper winding of escape magnet 13, armature and front contact of relay 10, to ground. Relays 9 and 10 being slow to release, remain energized during the sending of the first series of impulses and relay 9 at its upper armature and front contact maintains ground on the release 95 trunk over finder brush 4 to prevent the release of the finder.

100 Stepping magnet 11 is alternately energized and deenergized in response to the impulses to move the brush-shaft a desired number of steps in a primary direction. Upon the termination of the impulses, relay 10 7 remains energized and, after a time, slow release relay 10 is deenergized and opens the circuit of escape magnet 13 which deener-

gizes and releases the side switch into its second position.

When the second series of impulses is sent, the first deenergization of relay 7 completes 5 a circuit from ground, armature and back contact of relay 7, lower armature and front contact of relay 9, winding of relay 10, armature and back contact of busy relay 14, winding of secondary stepping magnet 15, 10 side-switch wiper 12 in its second position, to grounded battery. Relay 10 completes a circuit for escape magnet 13, as before, and remains energized during the sending of the 15 impulses, while stepping magnet 15 advances the brush-shaft in a secondary direction in response to the interruptions in the line circuit.

At the conclusion of the second series of impulses slow release relay 10 is again de- 20 energized and provides a test circuit for the escape magnet. This circuit extends from grounded battery, upper winding of escape magnet 13, armature and back contact of relay 10, winding of relay 14, upper armature and back contact of test relay 14, side- 25 switch wiper 16 in its second position, and test brush 17.

If the line called is idle, the idle condition will result in the absence of ground upon 30 test terminal 18, and since the test circuit of escape magnet 13 is opened at this point, the escape magnet will deenergize and release the side-switch wipers into their third position.

35 In the third position of the side switch a circuit will be completed for relay 19, from grounded battery, winding of relay 19, outer upper armature and back contact of magnet 13, side-switch wiper 16 in its third 40 position, to ground. Relay 19 at its armatures connects the line conductors to the connector brushes 20 and 21. A circuit is now completed for ringing relay 22 from grounded battery, side-switch wiper 12 in 45 its third position, upper armature and back contact of ringing cut-off relay 23, winding of relay 22, interrupter 24, to ground. When the brushes of the interrupter 24 are on conducting segments, the relay 22 will be 50 energized, and completes a ringing circuit to the called substation, this circuit extending from a source of alternating current indicated at 25, outer upper armature and front contact of relay 22, upper armature 55 and front contact of relay 19, connector brush 20 and its associated contact, the loop of the called subscriber's line including the substation bells, connector brush 21 and its associated contact, lower armature and 60 front contact of relay 19, inner upper armature and front contact of relay 22, to ground. The intermittent operation of relay 22 results in the projection of ringing current over the line at desired time intervals.

65 When the called subscriber answers and

removes his receiver from the hook, an energizing circuit for relay 8 will be completed when relay 22 is in a deenergized condition, this circuit extending from grounded battery, lower winding of relay 8, upper outer 70 armature and back contact of relay 22, upper armature and front contact of relay 19, connector brush 20 and its associated contact, the loop of the calling subscriber's line, connector brush 21 and its associated 75 contact, lower armature and front contact of relay 19, inner upper armature and back contact of relay 22, upper winding of relay 8, to ground.

The energization of relay 8 causes the re- 80 versal of the direction of current flow in the calling subscriber's line to operate a polarized message register (not shown) or similar device in the well-known manner. This current reversal is accomplished through 85 the upper armature and front contact and inner lower armature and front contact of relay 8.

At the outer lower armature of relay 8 a 90 circuit is completed for ringing cut-off relay 23 from grounded battery, side-switch wiper 12 in its third position, winding of relay 23, outer lower armature of relay 8, and off-normal contact 26 to ground.

Off-normal contacts 26, 27 and 28 are 95 closed when the switch makes its first primary step, contact 29 being opened at the same time.

Relay 23 energizes and locks itself to ground at contact 26 through its inner lower 100 armature and front contact. At its upper armature it permanently opens the circuit of ringing relay 22 and prevents the reoperation of this relay. The connection is now complete and the subscribers may converse. 105

At the termination of the conversation both parties replace their receivers, the replacing of the calling subscriber's receiver resulting in the deenergization of relay 7, 110 causing, in turn, the deenergization of relay 9. Relay 9 at its upper armature removes ground from the release trunk, which results in the release of the finder in the well-known manner. At the same time a circuit is closed for release magnet 30 from grounded battery, off-normal contact 27, lower armature and back contact of relay 9, armature and back contact of relay 7 to ground. The release magnet causes the restoration of 115 the switch and remains energized until its circuit is broken by the opening of off-normal contact 27 when the brushes are fully restored. The return of the brush shaft at the same time restores the side-switch wipers to their normal position in the usual manner. 120

125 Referring now to the point in the operation just after the second series of impulses has been sent, it will be assumed that the desired line is busy. In that case ground will

be connected to test terminal 18 through side-switch wiper 16 of some other connector in its third position. The escape magnet 13 will now remain energized, and since relay 14 is included in its circuit, relay 14 will also be energized, causing the application of busy-tone to the calling line. An alternating current is applied to relay 8 over a path from grounded battery, condenser 31, coil 32, middle lower armature and front contact of relay 14, upper winding of relay 8 to ground. The inductive action of this current on the windings of relay 8 causes a tone to be transmitted over the calling subscriber's line through condensers 33 and 34. The calling subscriber thereupon replaces his receiver and causes the release of the connector as previously described.

The operation of the circuits shown will now be described, in case the switch fails to operate correctly, or if the operation is such as to require some form of supervision.

The means for informing a supervising operator that the called subscriber has not answered within a predetermined time interval will first be discussed, it being assumed that the call has been successfully set up and that ringing current is being applied to the called line. At this time a circuit will extend from grounded battery, winding of slow pull-up relay 35, off-normal contact 28, side-switch wiper 36 in its third position, lower armature and back contact of ringing relay 22, winding of slow pull-up relay 44, lower armature and back contact of relay 23, off-normal contact 26, to ground. Relay 35 is of a type such that it will close its contacts only after having been energized for a predetermined period, but will restore to its normal condition quickly upon any opening of its circuit. A form of a dash-pot relay would be suitable for this purpose. Relay 44 is preferably of the thermo type and will require perhaps two or three minutes to attract its armature. Short interruptions in its circuit, however, will not interfere with the cumulative action of this relay. Therefore, in the circuit above traced, each deenergization of ringing relay 22, due to the operation of interrupter 24, will cause the restoration of relay 35, and it will not be sufficiently energized to operate its contacts. Relay 44, however, continues to build up and when it attracts its armature a circuit is completed from grounded battery, lamp 37, armature and front contact of relay 44, interrupter 38 to ground. The lamp 37 is caused to flash in this circuit. The lamp 37 is individual to the connector shown, and an operator, whose cord circuit is indicated at O, upon observing the flashing of the lamp, may insert a plug 39 into a jack 40 associated with lamp 37, and to which lead multiples of the trunk terminating in the

connector shown. She may then converse with the calling subscriber and inform him that the called subscriber does not answer. In this way the switch is not caused to remain in service for an undesirably long period of time.

If the called line has been found busy and the calling subscriber fails to release the connection, the supervisory operator will be informed in the following manner.

It is to be observed at this time that when the busy relay 14 was energized it established a locking circuit for itself through its innermost lower armature and contact, this circuit extending from grounded battery, upper winding of escape magnet 13, armature and back contact of relay 10, winding of relay 14, inner lower armature and front contact of relay 14, off-normal contact 26, to ground. Therefore, if the switch is not released within a given time after the application of the busy tone, relay 35 will be energized over a circuit from grounded battery, winding of relay 35, off-normal contact 28, side-switch wiper 36 in its second position, outer lower armature and contact of relay 14, to ground. Relay 35 upon energization closes a circuit for lamp 37, from grounded battery, lamp 37, outer armature and front contact of relay 35 to ground. At the same time a holding circuit for relay 9 is completed at the inner armature and front contact of relay 35. The operator at O, upon observing the lighting of lamp 37, inserts plug 39 into jack 40, as before, and upon hearing the busy signal may inform the calling subscriber that the line is busy. Since relay 14 is locked up independently of the busy or non-busy condition of the called line, relay 35 will remain energized and at its inner armature maintain ground on the circuit of relay 9 to prevent the release of the switch after the calling subscriber has replaced his receiver. The connector will, therefore, remain in its actuated condition and may be inspected with a view to determining whether the busy tone apparatus is operating properly.

The operator is able to ascertain the approximate nature of the trouble by the manner in which the lamp 37 is operated and by plugging in on the connection. If the lamp flashes, she will know that the trouble is merely due to the failure of the calling subscriber to release the connection in case the called subscriber does not answer within a given time. If the lamp burns steadily and she hears the busy tone upon plugging in, she will know that the calling subscriber has failed to release the connection upon hearing the busy tone. If, however, she plugs in upon observing the steady burning of lamp 37 and does not hear a busy tone, she will know that the trouble is more se-

rious and can take steps to have the switch inspected and the trouble removed.

If the switch should fail to move in a primary direction in response to the first series of impulses, the operator will be informed in the following manner: Upon the deenergization of slow release relay 10 the escape magnet 13 will not deenergize, since a locking circuit will be present through its 10 lower winding and lower armature and front contact, this circuit extending from grounded battery, winding of relay 35, normally closed contact 29, which has not been opened since the brush shaft failed to move, 15 lower armature and front contact of escape magnet 13, lower winding of escape magnet 13, to ground. This circuit locks the side switch in position 1, and also allows relay 35 to energize, signaling the operator as before, and also preventing the release of the 20 switch after the called subscriber replaces his receiver in response to the directions received from the operator at O, after she has plugged in the connection. It is to be noted 25 that the connector is again held in its actuated condition to allow inspection.

If, now, we assume that the switch operated correctly in response to the first series of impulses, but failed to move in a secondary direction upon receipt of the second set of impulses, the operation will be as follows: Upon conclusion of the second set of impulses, relay 10 will deenergize, but if the switch has not moved in a secondary direction escape magnet 13 will not deenergize, owing to a locking circuit which exists through its lower winding from grounded battery, secondary off-normal contact 41, side-switch wiper 42 in its second position, 30 lower winding of relay 13, to ground. The contact 41 is closed until the brush shaft is moved in a secondary direction. This locking circuit serves to hold the side switch in position 2, and a circuit is completed for relay 35 from grounded battery, winding of 35 relay 35, primary off-normal contact 28, side-switch wiper 36 in its second position, outer lower armature and back contact of relay 14, inner upper armature and front 40 contact of escape magnet 13, to ground. Relay 35 again operates to attract the attention of the supervisory operator and lock the switch in its actuated condition as before.

It is possible that trouble may arise even 45 after the switch brushes have been successfully placed in engagement with the terminals of called lines, due to the failure of the ringing current to start. This would happen as a result of the failure of relay 22 to 50 energize, and would result in a circuit being established from grounded battery, winding of relay 35, off-normal contact 28, side-switch wiper 36 in its third position, lower armature and back contact of relay 22,

winding of relay 44, inner lower armature 65 and back contact of relay 23, off-normal contact 26, to ground. The relays 35 and 44 are now connected in series, but the relay 35 will energize before relay 44, and operate its contacts to attract the attention of the operator and hold the switch against release, as previously described.

The invention has been shown applied to a connector circuit, but is not limited to use with connector circuits, since it can be readily applied to other circuits.

The structure of the switch described may be that of any well-known type of step-by-step two-motion switch, a suitable type being shown in Patent No. 815,176, Keith and J. and C. J. Erickson, March 13, 1906.

What is claimed is:

1. In an automatic telephone exchange system, subscribers' lines, an automatic switch for interconnecting said lines, a signal individual to said switch, a supervisory operator's position, and means for operating said signal to notify said operator that the switch has failed to function properly at some stage of its operation while operating 85 to interconnect two lines and means to variably operate said signal in accordance with the nature of the trouble to notify said operator of the approximate nature of the trouble.

2. In an automatic telephone exchange system, subscribers' lines, an automatic switch for interconnecting said lines, and automatic means to prevent the release of said switch in case it fails to operate correctly.

3. In an automatic telephone exchange system, subscribers' lines, an automatic switch for interconnecting said lines, automatic means to prevent the release of said switch in case it fails to operate correctly, and means to maintain said switch in that stage of operation at which incorrect operation occurred.

4. In an automatic telephone exchange 110 system, subscribers' lines, an automatic switch for interconnecting said lines, a supervisory operator's position, means for signaling said supervisory operator's position if said switch fails to function properly, 115 and means actuated simultaneously with said signaling means to prevent the release of said switch.

5. In an automatic telephone exchange system, subscribers' lines, an automatic 120 switch for interconnecting said lines, a supervisory operator's position, a signal thereat, a slow acting relay, a second slow acting relay, a divided circuit for said signal, one of the branches of said circuit being controlled at contacts of said first relay and the other branch of said circuit being controlled at contacts of said second relay, and means

- to energize one of said relays to operate said signal in case said switch operates incorrectly.
6. In an automatic telephone exchange system, subscribers' lines, an automatic switch for interconnecting said lines, a supervisory operator's position, a signal thereat, a relay slow to operate but quick to release, a second relay slow to act but not affected by short interruptions of its circuit while being energized, and means including said relays to operate said signals in a distinctive manner to notify said operator that the switch has failed to operate correctly and to notify said operator of the approximate nature of the trouble.
7. In an automatic telephone exchange system, subscribers' lines, an automatic switch for interconnecting said lines, a supervisory operator's position, a signal thereat, means to move said switch in a primary direction, means to move said switch in a secondary direction, means to signal a called subscriber, means to inform a calling subscriber that a called subscriber's line is busy, and means to operate said signal in case any of the previously mentioned means operate incorrectly.
8. In an automatic telephone exchange system, subscribers' lines, an automatic switch for interconnecting said lines, a supervisory operator's position, a signal thereat, means to move said switch in a primary direction, means to move said switch in a secondary direction, and means to operate said signal if said switch fails to move in either a primary or a secondary direction.
9. In an automatic telephone exchange system, subscribers' lines, an automatic switch for interconnecting said lines, a supervisory operator's position, a signal thereat, and means for operating said signal if a called subscriber fails to answer within a predetermined time interval.
- 45 10. In an automatic telephone exchange system, subscribers' lines, an automatic switch for interconnecting said lines, a supervisory operator's position, a signal thereat, means for informing the calling subscriber that a called line is busy, and means for operating said signal if the calling subscriber fails to release the connection in response to said informing means.
11. In an automatic telephone exchange system, subscribers' lines, an automatic switch for interconnecting said lines, a supervisory operator's position, a signal thereat, means to variably operate said signal in response to the occurrence of various kinds of trouble which may arise during operation of said switch, means to signal a called subscriber, and means to operate said signal if said signaling means fails to operate.
12. In an automatic telephone exchange system, subscribers' lines, an automatic switch for interconnecting said lines, a supervisory operator's position, a signal thereat, and automatic means for operating said signal if a called subscriber fails to answer within a predetermined time interval.
13. In an automatic telephone exchange system, subscribers' lines, an automatic switch for interconnecting said lines, a supervisory operator's position, a signal thereat, and means including an interrupter for operating said signal in a distinctive manner, if a called subscriber fails to answer within a predetermined time interval.
14. In an automatic telephone exchange system, subscribers' lines, an automatic switch for interconnecting said lines, a supervisory operator's position, a signal thereat, means for operating said signal continuously, and means including two interrupters for operating said signal intermittently if a called subscriber fails to answer within a predetermined time interval.

In witness whereof I hereunto subscribe my name this 24th day of November, A. D. 1916.

HENRY P. CLAUSEN.
